DESIGN FOR A MULTIPLE GEM MOUNTING

Joseph Granat, San Francisco, Calif.

Application October 29, 1937, Serial No. 72,501

Term of patent 7 years

To all whom it may concern:

Be it known that I, Joseph Granat, a citizen of the United States of America, residing at San Francisco, in the county of San Francisco and State of California, have invented a new, original, and ornamental Design for a Multiple Gem Mounting, of which the following is a specification, reference being had to the accompanying drawing, forming a part thereof.

Fig. 1 is a side elevation of a multiple gem mounting, showing my new design;

Fig. 2 is a top plan view thereof; and
Fig. 3 is a bottom plan view thereof.

I claim:—

The ornamental design for a multiple gem mounting, substantially as shown.

JOSEPH GRANAT.
